[57] ABSTRACT

In its simplest form the device includes a main body or frame having a first guide groove adapted to receive a substantially U-shaped arm with an aperture therethrough of a striker assembly, and second and third guide grooves aligned across the first guide groove to provide a passageway for a bolt sliding into and out of engagement with the U-shaped striker arm. A detent is provided to normally hold the bolt within the second guide groove against the force of spring means urging the bolt toward the third guide groove. Upon closure of the door the striker arm enters the first guide groove to turn the detent out of engagement with the bolt, whereupon the bolt is caused by the spring means to become partly received in the third guide groove through the aperture in the striker arm, thereby engaging the same in the fully latched position. The striker arm can also be engaged in the secondary latched position by abutments formed in the bolt. There are further disclosed herein several other embodiments of the invention.

DOOR LATCH DEVICE

BACKGROUND OF THE INVENTION

This invention relates generally to door latch devices, and more specifically to a door latch device of a sliding bolt-type, especially adapted for vehicles, operable to position the door in a closed position relative to the vehicle body in cooperation with a striker assembly of the type having a substantially U-shaped striker arm.

SUMMARY OF THE INVENTION

It is an object of this invention to provide a door latch device incorporating a linearly sliding bolt adapted to positively engage a substantially U-shaped arm of a striker assembly, in such a manner that the overall door latch system can withstand sufficient longitudinal, transverse and inertia loads in the secondary or fully latched position.

Another object of the invention is to provide a door latch device of the above described type which is capable of engaging the striker arm without causing any substantial collision thereof with the sliding bolt at the time of door closure.

A further object of the invention is to provide a door latch device of the type described wherein minimum manual effort is required to release the striker arm from the device at the time of door opening.

A further object of the invention is to provide a door latch apparatus of the type described wherein the striker arm can be released from the device with a highly reduced stroke of a door handle or the like.

A still further object of the invention is to provide a door latch device of the type described, including means for keyless locking and self-cancelling operations.

With these objects in view and the other objects hereinafter set forth, this invention provides a door latch device for cooperative use with a striker assembly of the type having a substantially U-shaped striker arm with an aperture therethrough, which comprises a frame having a first guide groove for receiving the striker arm when the door is closed, a second guide groove extending normally to and communicating with the first guide groove, and a third guide groove aligned with the second guide groove across the first guide groove. A bolt adapted to be slidable along and through the second and third guide grooves is normally retained in the second guide groove by detent means against the force of spring means. Thus, upon closure of the door, the striker arm enters the first guide groove to disengage the detent means from the bolt thereby causing the same to become partly received in the third guide groove across the first guide groove.

The features which are believed to be novel and characteristic of this invention are set forth with particularity in the appended claims. The invention itself, however, both as to its construction and mode of operation, together with the further objects and advantages thereof, will be best understood from the following description taken in connection with the accompanying drawings which illustrate some preferred embodiments of the invention.

BRIEF DESCRIPTION OF THE DRAWINGS

FIG. 1 is a front elevational view of a door latch device constituting a preferred embodiment of the invention;

FIG. 2 is a front elevational view showing the inner details of the device of FIG. 1 with its front cover removed;

FIG. 3 is a view similar to FIG. 2 but showing the device in a secondary latched position;

FIG. 4 is also a view similar to FIG. 2 but showing the device in the fully latched position;

FIG. 5 is a rear elevational view showing the device of FIG. 1 in the fully latched position;

10 FIG. 6 is a vertical sectional view taken along the plane of line VI—VI in FIG. 4;

FIG. 7 is a front elevational view of a striker assembly for use with the device of FIG. 1;

15 FIG. 8 is a side elevational view of the striker assembly of FIG. 7;

FIG. 9 is a front elevational view of another preferred embodiment of the invention;

FIG. 10 is a rear elevational view of the device of FIG. 9;

20 FIG. 11 is a right hand side elevational view of the device of FIG. 9;

FIG. 12 is a front elevational view showing the inner details of the device of FIG. 9 with the front cover removed;

FIG. 13 is a vertical sectional view taken substantially along the plane of line XIII—XIII in FIG. 12;

FIG. 14 is a view similar to FIG. 13 but showing the device in the secondary latched position;

FIG. 15 is also a view similar to FIG. 13 but showing the device in the fully latched position;

FIG. 16 is a vertical sectional view taken substantially along the plane of line XVI—XVI in FIG. 15;

FIG. 17 is a front elevational view of still another preferred embodiment of the invention, in which the front cover is shown partly broken away to illustrate the inner details of the apparatus;

FIG. 18 is a vertical sectional view taken substantially along the plane of line XVIII—XVIII in FIG. 17;

FIG. 19 is a rear elevational view of the device of FIG. 17;

FIG. 20 is a rear elevational view of main and auxiliary bolts in the device of FIG. 17;

FIG. 21 is a front elevational view showing the device of FIG. 17 in the secondary latched position, with the front cover removed;

FIG. 22 is a view similar to FIG. 21 but showing the device in the fully latched position;

FIG. 23 is also a view similar to FIG. 21 but showing how the striker arm is released from the apparatus;

50 FIG. 24 is a vertical sectional view taken substantially along the plane of line XXIV—XXIV in FIG. 23;

FIG. 25 is a front elevational view of a further preferred embodiment of the invention in which the front cover is shown partly broken away to illustrate the inner details of the device;

FIG. 26(A) is a front elevational view showing the detailed configuration of the frame in the device of FIG. 25;

60 FIGS. 26(B) and 26(C) are mutually orthogonal, enlarged side views of a pin used in the device illustrated in FIG. 25;

FIG. 27 is a rear elevational view of the device of FIG. 25;

65 FIG. 28 is a left hand side elevational view of the device of FIG. 25;

FIG. 29 is a vertical sectional view taken substantially along the plane of line XXIX—XXIX in FIG. 25;

FIG. 30 is a front elevational view showing in greater detail the bolt and some associated parts in the device of FIG. 25;

FIG. 31 is an exploded perspective view showing on an enlarged scale the second and fourth levers and some associated parts in the device of FIG. 25;

FIG. 32 is a view similar to FIG. 27 but showing the device in the locked position, with the striker arm in the fully latched position;

FIG. 33 is also a view similar to FIG. 27 but explanatory of keyless locking and self-cancelling operations performed by the apparatus;

FIG. 34 is a front elevational view of a still further preferred embodiment of the invention in which the front cover is shown partly broken away to illustrate the inner details of the device;

FIG. 35 is a rear elevational view of the device of FIG. 34;

FIG. 36 is a right hand side elevational view of the device shown in FIG. 35;

FIG. 37 is a left hand side elevational view of the device shown in FIG. 35;

FIG. 38 is a vertical sectional view taken substantially along the plane of line XXXIX—XXXIX in FIG. 35;

FIG. 39 is a view similar to FIG. 35 but showing the device in the locked position, with the striker arm in the fully latched position; and

FIG. 40 is also a view similar to FIG. 35 but explanatory of the keyless locking and self-cancelling operations performed by the device.

DETAILED DESCRIPTION

The invention will now be described more specifically in terms of a first preferred embodiment thereof illustrated in FIGS. 1 through 6. The reference numeral 1 in FIG. 1 designates the main body or frame of the example door latch device which can be conveniently molded of polyacetals or like synthetic resins having good dimensional stability and abrasion resistance. The apparatus includes, however, a front cover 2 which preferably is made of a suitable metal.

FIG. 2 illustrates the inner details of the door latch device with the front cover 2 removed. A relatively deep first guide groove 1f extends horizontally relative to the frame 1 to receive the U-shaped arm 9a of a striker assembly 9 of well known construction shown in FIGS. 7 and 8. Formed at right angles with this first guide groove 1f are vertically aligned, relatively shallow second and third guide grooves 1a and 1b. A bolt 4 preferably made of metal is received in the second guide groove 1a so as to be slidable up and down therein, being guided by a pair of confronting walls 1c and 1d of the second guide groove. The bolt 4 is recessed at its lower edge to define abutments 4a and 4c, and a sloping surface is formed at 4b to provide a further abutment for purposes hereinafter made apparent. This bolt 4 is urged downward by a helical compression spring 6 accommodated in a recess 4d at the upper end of the bolt, the spring 6 being fixedly supported at its upper end by a bracket 3a formed integrally with a rear cover 3 of the device, as will be seen also from FIG. 6.

A relatively shallow depression 1j and a relatively deep depression 1k are formed in the frame 1, and posts or pins 1h and 1i are formed on the depressions 1j and 1k respectively, the pins being molded in one piece with the frame 1 in this embodiment of the invention. The pin 1h is somewhat loosely received in a bore

5c of a detent 5 having a notch 5a adapted to engage the aforesaid abutment 4c of the bolt 4, thereby normally holding the same in the inoperative or fully elevated position illustrated in FIG. 2. The other pin 1i is adapted to support a spring 7 having its end 7a engaged with the detent 5 to resiliently urge the same in the counterclockwise direction as seen in FIG. 2. The other end 7b of the spring 7 is fixedly anchored to the frame 1. An elongate pin 8 is formed substantially integrally with the bolt 4 so as to extend backward through a slot 1n formed in the frame 1, as will be seen from FIGS. 5 and 6.

The striker assembly 9 illustrated in FIGS. 7 and 8 is assumed to be bolted or otherwise fastened to the vehicle body as through holes 9b. The door latch apparatus proper shown in FIGS. 1 through 6 can also be bolted to the vehicle door through holes 1m, 2b and 3b that are formed in its frame 1 and front and rear covers 2 and 3, respectively.

20 The first preferred embodiment of the invention being constructed as described above, the U-shaped arm 9a of the striker assembly 9 enters the first guide groove 1f of the frame 1 through the corresponding slot formed in the front cover 2 upon closure of the vehicle door. In this instance, the U-shaped striker arm 9a moves toward the tip 5b of the detent 5 to cause the same to turn through a predetermined angle against the force of the spring 7, whereupon the bolt 4 is permitted to be moved downward by the spring 6 until its abutments 4a and 4c come into contact with the striker arm as illustrated in FIG. 3. This state represents the so-called secondary latched position.

As the striker arm 9a advances further from this secondary latched position, the abutment 4c of the bolt 4 becomes disengaged therefrom so that the bolt is caused to move further downward by the spring 6 until its abutment 4c comes into contact with the wall portion 1g defining the first guide groove 1f, with the lower end portion of the bolt received in the third guide groove 1b of smaller width. The striker arm 9a is now securely retained by the bolt 4, being in contact with its abutment 4b as illustrated in FIG. 4. This is the state known as the fully latched position.

45 For opening the door, the pin 8 is manually lifted against the force of the spring 6 through any known or suitable means, not shown, thereby causing the bolt 4 to release the U-shaped arm 9a of the striker assembly 9. As the striker arm 9a progressively moves out of the first guide groove 1f, the bolt 4 is held in its fully elevated position shown in FIG. 2 by the detent 5 with the abutment 4c of the former in engagement with the notch 5a of the latter.

50 It will be understood from the foregoing description of the first embodiment of the invention that any forcible contact between the metal bolt 4 and the striker arm 9a is avoided at the time the door is closed, thereby reducing the possibility of damage to the latch device and preventing the production of any unpleasant sound at the time of door closure.

60 Another preferred embodiment of the invention is illustrated in FIGS. 9 through 16, in which parts corresponding to those shown in FIGS. 1 through 8 are designated by like reference characters and will not necessarily be described in full detail. As in the preceding embodiment, the main body or frame 1 of the latch device having the front and back covers shown in FIGS. 9 and 10 is formed with the relatively deep first guide

groove 1f extending horizontally as best shown in FIG. 12 to receive the U-shaped arm 9a of the striker assembly 9 set forth previously with reference to FIGS. 7 and 8. Also as in the preceding example the bolt 4 is slidably received in the relatively shallow second guide groove 1a which is aligned with the third guide groove 1b in a direction at right angles with the first guide groove 1f.

As best shown in FIGS. 10 and 12, a first lever 10 is turnably pinned at 11 to the rear cover 3, the first lever being turned counterclockwise as seen in FIG. 12 as its edge 10a contacts the U-shaped arm 9a of the striker assembly upon closure of the vehicle door. A second lever 12 is likewise turnably pinned at 13 to the rear cover 3, and a spring 14 coiled around the pin 13 has one arm 14a thereof fixedly supported by a support 12a formed on the second lever 12 and the other arm 14b fixedly supported by a support 3a formed on the rear cover 3. The second lever 12 is thus resiliently urged to turn counterclockwise as seen in FIG. 12. A helical extension spring 16 has its terminal hooks 16a and 16b caught by supports 12b and 10b formed on the second lever 12 and first lever 10 respectively. The coil portion 16c of this extension spring 16 has a relatively high spring constant such that upon clockwise, turning as seen in FIG. 10, of the first lever 10, the second lever 12 is caused to turn counterclockwise against the force of the spring 14.

As set forth previously in connection with the example illustrated in FIGS. 1 through 6, the detent 5 is turnably supported on the pin 1h formed on the depression 1j of the frame 1, and the notch 5a of this detent is normally in engagement with the abutment 4c of the bolt 4 to retain the latter in its fully elevated or inoperative position shown in FIG. 12 in particular. The detent 5 is, of course, energized in the counterclockwise direction as shown in FIG. 12, by the spring 7 coiled around the pin 1i formed on the depression 1k of the frame 1.

As best illustrated in FIG. 13, holes 4e and 4f of different diameters are formed coaxially through a depressed part 4d of the bolt 4, and a pin 17 telescopically received in these holes in resiliently urged by a helical compression spring 18 so that its enlarged head 17d will abut against the front cover 2. As will be seen from FIGS. 10 and 12, the aforesaid second lever 12 is bent twice substantially into the shape of a Z and extends through a window 1p of the frame 1 so that its free end 12c rests on the head 17a of the pin 17.

The upper end of the bolt 4 is bifurcated as indicated at 4h to loosely receive one end of a release lever 19 which is turnable on a pin 20 revolvably extending through its bore 19a and bores 4g formed in the bifurcated end 4h of the bolt, as indicated in FIGS. 13 and 14, respectively. The release lever 19 includes a downward extension 19b which is fitted in a slot 17c, FIG. 13, of the pin 17.

The operation of this second preferred embodiment of the invention is such that upon closure of the vehicle door, the U-shaped arm 9a of the striker assembly 9 moves into the first guide groove 1f of the frame 1 toward the tip 5b of the detent 5 and the edge 10a of the first lever 10 as will be best seen from FIG. 12. The first lever 10 is first caused by the striker arm to turn counterclockwise on the pin 11 thereby pulling the spring 16 downward. As a consequence, the second lever 12 is urged to turn clockwise on the pin 13 and thus exerts downward pressure on the bolt 4 since the

free end 12c of the second lever is urged against the head 17a of the pin 17 extending transversely therethrough. However, since the bolt 4 is yet held arrested by the detent 5, the bolt remains in its fully elevated position, whereby tensile force is stored in the spring 16.

As the striker arm 9a advances further along the first guide groove 1f, the detent 5 is caused to turn clockwise as viewed in FIG. 12, thereby disengaging the abutment 4c of the bolt 4 from its notch 5a. Thereupon the bolt 4 is caused to drop forcibly into the secondary latched position shown in FIG. 14 by virtue of the tensile force that has been stored in the spring 16. The abutments 4a and 4c of the bolt 4 are now in contact with the striker arm 9a, and the vehicle door is not yet fully closed.

With further advancement of the striker arm 9a, out of engagement with the bolt 4, the tensile force still left in the spring 16 causes the bolt to drop again into the fully latched position shown in FIG. 15, in which the 20 striker arm is in contact with the abutment 4b of the bolt. The bolt 4 is subject to downward pressure while the door is thus fully closed.

For opening the door, the free end 19c of the release lever 19 is manually lifted by means not shown in the 25 drawings thereby causing the rightward displacement, as seen in FIG. 16, of the pin 17 by its downward extension 19b against the force of the spring 18. The head 17a of the pin 17 thus moves out of engagement with the free end 12c of the second lever 12, whereupon the bolt 4 becomes free of the downward pressure which has been exerted by the spring 16, although there still remains some frictional resistance between the striker arm 9a and the abutment 4b of the bolt.

The release lever 19 can now be raised with minimum exertion of force on the part of the operator, and the bolt 4 becomes completely disengaged from the 30 striker arm 9a. As the striker arm thus substantially moves out of the first guide groove 1f, the second lever 12 is caused to turn counterclockwise, as seen in FIG. 15, by the spring 14 because then the second lever is no longer subject to the tensile force of the spring 16. With this counter-clockwise rotation of the second lever 12, the first lever 10 is turned clockwise via the 35 spring 16. In this manner, the second lever 12 will ordinarily return to its position shown in FIG. 12.

If the free end 12c of the second lever 12 fails to return to the position of FIG. 12 before the head 17a of the pin 17 projects out of the hole 4e of the bolt 4, then the free end of the second lever will be caused by the 40 spring 14 to slide along the sloping surface 17d of the pin head 17a thereby pressing the pin back into the hole 4e against the force of the spring 18. The second lever 12 thus returns to its position above the pin 17 as shown in FIG. 12. It will be apparent, of course, that upon return to its fully elevated position also shown in FIG. 12, the bolt 4 is arrested by the detent 5 biased by the 45 spring 7. The initial inoperative state of the latch apparatus is thus restored.

As will be apparent from the foregoing description, 50 it is a particular advantage of this second embodiment of the invention that the minimum exercise of manual force is required on the part of the operator to release the bolt 4 from its position in engagement with the striker arm 9a because the bolt is not subject to the tensile force of the spring 16 which is utilized to ensure the positive engagement of the bolt with the striker arm. This advantage, moreover, is attained without the 55

slightest sacrifice in the ability of the latch apparatus to withstand high longitudinal, transverse and inertia loads in its secondary or fully latched position.

A third preferred embodiment of the invention is illustrated in FIGS. 17 through 24, in which parts corresponding to those of the first and second embodiments are also designated by like reference characters and will not necessarily be described in any detail in the succeeding description of this third embodiment. As in the preceding embodiments, the latch device includes the main body or frame 1 sandwiched between the front cover 2 and the rear cover 3, as best shown in FIG. 18. The front cover 2 is formed with the slot 2a, FIG. 17, in registration with the relatively deep first guide groove 1f formed in the frame 1 to receive the U-shaped arm 9a of the striker assembly shown in FIGS. 7 and 8.

A main bolt 4M is slidably received in the relatively shallow second guide groove 1a, and this main bolt is provided with an auxiliary bolt 4S which is to be received in the relatively shallow third guide groove 1b. The lower end of the second guide groove 1a is slightly expanded to the right as seen in FIG. 17. The bifurcated upper end of the main bolt 4M is pinned at 23 to one end of the release lever 19 which extends backwardly through the slot 24 formed at the bottom of the first guide groove 1a, and a pair of helical compression springs 25 are mounted in parallel spaced relationship between the upper wall of the first guide groove 1a and the shoulders of the main bolt 4M so that the latter is resiliently urged downward.

As will be seen from FIGS. 17 and 18, the main bolt 4M is formed with a stepped pin 26 hereinafter set forth in further detail, and a step 4h of the shape illustrated in FIG. 17 is formed on that surface of the main bolt confronting the front cover 2. Moreover, a depression 4i is formed on the same surface of the main bolt 4M, and a stepped transverse hole 4j is formed approximately centrally of the depression 4i to receive a stepped pin 29 by which the auxiliary latch 4S is eccentrically supported within the depression 4i.

The aforesaid pin 26 received in the hole 4g of the main bolt 4M has a semicircular indentation on its head 26b and is resiliently urged forwardly by a helical compression spring 27 accommodated in the hole 4g. The rear end of the pin 26 projecting through the slot 24 of the frame 1 has a slot 26a adapted to engage the downward extension 19b of the release lever 19, as best seen in FIGS. 18 and 19.

The auxiliary bolt 4S has arcuate edges 4Sb and 4Sc, and the arcuate edge 4Sb is adjacently formed with an abutment 4Se while the other arcuate edge 4Sc is adjacently formed with an abutment 4Sd. This auxiliary bolt is resiliently urged in the clockwise direction, as seen in FIG. 17, by a spiral spring 30 best illustrated in FIG. 20, but the clockwise rotation of the auxiliary bolt is normally prevented as it contacts the step 4h of the main bolt 4M.

As in the preceding embodiments, the detent 5 urged to turn counterclockwise by the spring 7 is provided to engage the lower end of the main bolt 4M with its notch 5a, so that the main bolt together with the auxiliary bolt 4S is normally retained in the position shown in FIGS. 17 and 18.

The third preferred embodiment of the invention being constructed substantially as described above, the U-shaped arm 9a of the striker assembly 9 enters the

first guide groove 1f to come into contact with the arcuate edge 4Sb of the auxiliary bolt 4S upon closure of the vehicle door. Since the auxiliary bolt is now held immovable relative to the main bolt 4M as previously mentioned, the U-shaped striker arm 9a advances in sliding contact with the arcuate edge 4Sb of the auxiliary bolt thereby causing the same to move upwardly together with the main bolt against the forces of the springs 25. When the striker arm has passed under the arcuate edge of the auxiliary bolt 4S, both the main and auxiliary bolts 4M and 4S are caused by the springs 25 to drop to the initial or secondary latched position shown in FIG. 21, in which the abutment 4Se of the auxiliary bolt is in contact with the striker arm. Although the vehicle door is not yet completely closed, the disengagement of the striker arm 9a from the latch apparatus is prevented since the counterclockwise turn of the auxiliary bolt 4S does not take place due to the contact of its abutment 4Sd with the head 26b of the pin 26 which is now held in its forward position shown in FIG. 18.

As the striker arm 9a advances further along the first guide groove 1f, the main bolt 4M becomes disengaged from the detent 5 and is caused by the springs 25 to drop, together with the auxiliary bolt 4S, to the fully latched position shown in FIG. 22, in which the lower portion of the auxiliary bolt is received in the third guide groove 1b. The striker arm 9a is now securely retained within the latch apparatus by both the main and auxiliary bolts 4M and 4S. It is to be noted that the rotation of the auxiliary bolt relative to the main bolt is prevented throughout the complete process of door closure.

The vehicle door thus closed can be opened simply by lifting the release lever 19 as shown in FIG. 24. Both the main and the auxiliary bolts 4M and 4S are elevated against the forces of the springs 25 with the upward travel of the release lever 19 along the slot 24. Moreover, as the release lever is turned upwardly on the pin 23, its downward extension 19a causes the retraction of the pin 26 against the force of the spring 27, with the result that the auxiliary bolt 4S becomes disengaged from the pin 26 as the head 26b of the latter moves out of contact with the abutment 4Sd of the former. As soon as the lower portion of the auxiliary bolt 4S has risen out of the third guide groove 1b, therefore, the retracting striker arm 9a will engage the abutment 4Se of the auxiliary bolt to cause the same to turn counterclockwise on the pin 29 against the force of the spiral spring 30 as illustrated in FIG. 23. During this counterclockwise rotation of the auxiliary bolt 4S, its abutment 4Sd moves through the semicircular indentation on the pin head 26b as seen in FIG. 24. As the striker arm 9a thus moves out of the first guide groove 1f, the detent 5 is caused by the spring 7 to engage the main bolt 4M again. The auxiliary bolt 4S is likewise caused by its spring 30 to return to its initial position, thus engaging the head 26b of the pin 26 again as the release lever 19 is released.

It will be apparent from the foregoing description of this third embodiment of the invention that the striker arm 9a can be disengaged from the latch device as soon as the auxiliary bolt 4S has risen out of the third guide groove 1b to move from the fully latched position back to the secondary latched position shown in FIG. 21. Hence, the upward stroke of the release lever 19 neces-

sary to open the door is reduced to almost one half that of the prior art apparatus.

FIGS. 25 through 34 illustrates a further preferred embodiment of the invention which may be considered as a modification of the second described embodiment shown in FIGS. 9 through 16. The latch device shown in FIGS. 25 through 34 also included the main body or frame 1 having the first guide groove 1f adapted to receive the U-shaped arm 9a of the striker assembly 9, FIGS. 7 and 8, and the second and third guide grooves 1a and 1b which are aligned in a direction at right angles with the first guide groove 1f, as best illustrated in FIG. 26(A).

With particular reference to FIGS. 25 and 27, a bolt 104 is slidably received in the second guide groove 1a. A first lever 110 is pinned at 111 to the rear cover 3, in such a manner that the first lever will be turned counterclockwise, as seen in FIG. 25, as its edge 110a contacts the advancing arm 9a of the striker assembly at the time of door closure. A second lever 112 is also turnably pinned at 113 to the rear cover 3, and a spring 114 coiled around the pin 113 has one of its arms 114a fixedly supported by the support 3a on the rear cover 3 and the other arm 114b fixedly supported by a support 112a on the second lever 112, so that this second lever is urged to turn clockwise as seen in FIG. 27. Another spring 116 having a relatively high spring constant has its terminal hooks 116a and 116b engaged with supports 112b and 110b that are formed on the second lever 112 and the first lever 110 respectively. No substantial tensile force is normally exerted on the coil portion 116c of this spring 116. However, when the first lever 110 has been caused by the advancing striker arm 9a to turn counterclockwise as seen in FIG. 25, the second lever 112 will be caused to turn clockwise via the spring 116.

As best shown in FIG. 26(A), the relatively shallow depression 1j and the relatively deep depression 1k are formed on the front face of the frame 1, and the posts or pins 1h and 1i are formed on the depressions 1j and 1k respectively. The pin 1h is received in the bore 105c of a detent 105 to turnably support the same, the detent 105 having a notch 105a and a tip 105b which projects into the first guide groove 1f as shown in FIG. 25. Normally, the notch 105a of the detent 105 is in engagement with the abutment 104c of the bolt 104 thereby retaining the same in its fully elevated position. A spring 107 coiled around the aforesaid pin 1i has its arm 107b fixedly supported by the wall 1q, FIG. 26(A), of the depression 1k and its other arm 107c held against the detent 105 to urge the same in the counterclockwise direction as seen in FIG. 25.

As seen in FIG. 29, a depression 104d is formed on the front face of the bolt 104, and holes 104e and 104f of different diameter are formed coaxially through the bolt to slidably receive a pin 117 having enlarged head 117a. A helical compression spring 118 is accommodated within the hole 104e so that the head 117a of the pin 117 is urged against the front cover 2. Resting on this pin head 117a is the free end 112c of the second lever 112 extending through the window 1p, FIG. 26(A), of the frame 1, being bent substantially into the shape of a Z as will be seen also from FIGS. 25 and 27.

As illustrated in FIG. 25 and in more detail in FIG. 30, the bolt 104 has its upper end bifurcated as indicated at 104h, and a release lever 119 is turnably supported by a pin 120 extending through the holes 104g

of the bifurcated bolt end 104h and the hole 119a of the release lever. The downward extension 119b of the release lever is somewhat loosely received in the recess 117c of the pin 117 as best shown in FIG. 29. It is to be noted that since the force of the spring 114, FIG. 27, is sufficiently less than that of the spring 116, the clockwise turn of the first lever 110 results in the counterclockwise rotation of the second lever 112. The construction of this fourth embodiment of the invention as so far described is substantially the same as that of the FIGS. 9 to 16 embodiment. The characteristic features of the fourth embodiment will be understood from the following description.

As best shown in FIGS. 27 and 28, a third lever 219 is turnably riveted at 229 to a lateral expansion 110d of the first lever 110 and is urged in the clockwise direction, as seen in FIG. 27, by a helical expansion spring 225 extending between the spring supports 219a and 110e that are formed substantially integrally with the third lever 219 and the first lever 110, respectively. The clockwise rotation of this third lever is normally prevented by a stop 110f formed on the lateral expansion 110d of the first lever 110.

Also as shown in FIGS. 27 and 28, and in further detail in FIG. 31, a fourth lever 220 in the form of a bell crank is supported by the same pin 113 as the second lever 112 but is turnable independently of this second lever. The fourth lever 220 includes bends 220a and 220b and a hole 220c. A helical extension spring 228 has its terminal hooks caught in the hole 220c of the fourth lever 220 and a hole 3c formed in a bracket 3a of the rear cover 3, so that the fourth lever is urged in the counterclockwise direction as seen in FIG. 27. A stop 1r is formed on the frame 1 to normally hold the fourth lever 220 in the illustrated position against the force of the spring 228.

A locking lever 221 turnably pinned at 231 to the rear cover 3 is adapted to hold the latch apparatus in a locked or unlocked position as required with the aid of a spring 227 and stops 3d and 3e formed on the rear cover 3.

An opening lever 222 is turnably pinned at 230 on the locking lever 221 and is urged in the clockwise direction, as seen in FIG. 27, by a helical extension spring 226 having its terminal hooks caught in a hole 221a of the locking lever and a hole 222d of the opening lever. The opening lever 222 includes a downward extension 222c adapted to engage the bend 220a of the fourth lever 220 when the latch device is in the locked position and to disengage the same when the device is in the unlocked position.

An inside opening lever 223 best illustrated in FIG. 28 is turnably pinned at 232 on a bracket 3g formed on the rear cover 3, and the upper end 223a of this inside opening lever is disposed in a position engageable with the lateral extension 222b, FIGS. 25 and 27, of the aforesaid opening lever 222. A helical extension spring 224 seen in FIGS. 25, 27 and 28 has its terminal hooks caught in a hole 219b formed in the third lever 219 and a hole 221b formed in the locking lever 221, in such a manner that the spring 224 is normally unloaded. It is to be noted, however, that the tensile force of this spring 224 is greater than that of the spring 225 extending between the first lever 110 and the third lever 219.

Proceeding to the description of operation of this fourth embodiment of the invention, the U-shaped arm 9a of the striker assembly 9 shown in FIGS. 7 and 8 en-

ters the first guide groove 1f of the frame 1 toward the edge 110a of the first lever 110 and the tip 105b of the detent 105 upon closure of the vehicle door. The first lever 110 is first caused by the advancing striker arm 9a to turn counterclockwise, as seen in FIG. 25, on the pin 111 thereby exerting tension on the spring 116. The second lever 112 is thus loaded by the spring 116 in the clockwise direction, as seen in FIG. 25, to apply downward pressure to the bolt 104 by its free end 112c which is urged against the head 117ia of the pin 117 as best illustrated in FIG. 29. However, since the abutment 104c of the bolt 104 is still in engagement with the notch 105a of the detent 105, the spring 116 is temporarily held extended to store the energy exerted thereon.

The further advancement of the striker arm along the first guide groove 1f causes disengagement of the detent 105 from the bolt 104, with the result that the bolt is forced down to the secondary latched position by virtue of the energy that has been stored in the spring 116. As previously set forth, the abutments 104a and 104c of the bolt 104 are in contact with the striker arm in this secondary latched position.

As the striker arm advances further, the bolt 104 is again forced down to the fully latched position by virtue of the energy still remaining in the spring 116. The bolt 104 is now partly received in the third guide groove 1b and is in contact with the striker arm at its abutment 104b. The door latch apparatus and the striker assembly thus fully engaged is capable of withstanding a sufficiently large transverse load as the bolt is supported by the walls 1d and 1k of the second and third guide grooves 1a and 1b, and a sufficiently large longitudinal load as the bolt is supported by the wide face of the front cover 2.

If now a locking knob, key or the like, not shown, is turned to lock the striker arm in the above described fully latched position, the locking lever 221 assumes the elevated position shown in FIG. 32. Since the opening lever 222 is also turned counterclockwise with the locking lever 221, its downward extension 222c is now incapable of engaging the bend 220a of the fourth lever 220, so that the vehicle door cannot be opened if its outside handle or inside handle, not shown, is manipulated to turn the opening lever 222.

In order to open the door the opening lever 222 is turned counterclockwise as seen in FIG. 27 by exerting pressure on its upward extension 222a by the manipulation of the outside handle or by exerting pressure on its lateral extension 222b via the inside opening lever 223 by the manipulation of the inside handle. During this counterclockwise rotation of the opening lever 222, its downward extension 222c engages the bend 220a of the fourth lever 220 and causes the same to turn clockwise on the pin 113, with the result that the bend 220b of the fourth lever 220 raises the tip 119c of the release lever 119 as indicated by the dot-and-dash lines in FIG. 27. Since the release lever 119 is turnable up and down on the pin 120, its downward extension 119b causes retraction of the head 117a of the pin 117 into the hole 104e of the bolt 104 against the force of the spring 118 by engaging the rear end of its recess 117c, as will be seen from FIGS. 29, 26(B), and 26(C). The free end 112c of the second lever 112 is thus disengaged from the pin head 117a, while the bolt 104 is raised by the release lever to its fully elevated position to disengage the striker arm from the latch apparatus.

This fourth embodiment of the invention is also capable of performing a self-cancelling operation as set forth hereinbelow. It is now assumed that while the door is open, the locking lever 221 is turned to the locking position by the locking knob or the like as shown in FIG. 33, and that the door is then closed without manipulating the outside handle, that is, with the opening lever 222 left in the position indicated by the dot-and-dash lines in FIG. 33. The striker arm advancing along the first guide groove 1f causes the clockwise rotation of the first lever 110, with the result that the third lever 219 is displaced downward until its motion is arrested by the stop 3f formed on the rear cover 3. This downward displacement of the third lever 219 exerts tension on the spring 224 thereby returning the locking lever 221 to the unlocking position. The continued advancement of the striker arm along the first guide groove 1f causes further clockwise rotation of the first lever 110. Since now the third lever 219 is already in contact with the stop 3f, the right hand end, as seen in FIG. 33, of the third lever is caused to turn counterclockwise on the pin 229 against the force of the spring 225. Thus, when the striker arm has reached the fully latched position, the right hand end of the third lever 219 is returned to a position substantially the same as that it assumed before the door was closed. The locking lever 221 can now be turned to the locking position in the usual manner by the locking knob or the like.

According to this fourth embodiment, it is further possible to lock the striker arm in the fully latched position within the latch apparatus without use of the key. Let it be assumed that the locking knob is manipulated to turn the locking lever 221 to the locking position as shown in FIG. 33 while the door is open, and that the door is successively closed with the opening lever 222 held in the position indicated by the solid lines in FIG. 33 by the intentional manipulation of the outside handle. The first lever 110 is turned clockwise as aforesaid by the advancing striker arm, so that the third lever 219 is displaced downwardly until its motion is arrested by the stop 3f on the rear cover 3. The third lever 219 thus causes the locking lever 221 to tend to return to the unlocking position via the spring 224. However, since the downward extension 222c of the opening lever 222 abuts on the top 220d of the bend 220a of the fourth lever 220, the locking lever 221 is unable to return to the unlocking position. As the striker arm continues advancing along the first guide groove 1f, the first lever 110 is further turned clockwise, with the result that the right hand end 219b of the third lever 219, now in contact with the stop 3f, is caused to turn counterclockwise on the pin 229. When the striker arm has reached the fully latched position, the right hand end of the third lever 219 is returned to the position substantially the same as that it assumed before the door was closed. No substantial tensile force is now exerted on the spring 224, so that the locking lever 221 will not return to the unlocking position if the outside handle is released to permit the opening lever 222 to return to the position indicated by the dot-and-dash lines in FIG. 33. The keyless locking of the vehicle door is thus accomplished.

A fifth preferred embodiment of the invention is illustrated in FIGS. 34 through 40, in which parts corresponding to those of the example illustrated in FIGS. 25 through 34 are indicated by like reference characters and will not necessarily be described in any detail in the

succeeding description of the fifth embodiment. The configuration of this fifth embodiment as shown in FIG. 34 is substantially the same as that shown in FIG. 25. As seen in further detail in FIG. 35, the fifth embodiment also comprises the bolt 104, the detent 105, the first lever 110, the second lever 112, the release lever 119, the third lever 219 and so forth which are arranged in substantially the same manner as in the example shown in FIGS. 25 through 34.

There are additionally included in this fifth embodiment a fourth lever 320 and a fifth lever 321. The fourth lever 320 is turnably pinned at 333 on a bracket 3a formed on the rear cover 3, while the fifth lever 321 is turnably pinned at 334 on another bracket 3m formed on the rear cover 3, as will be seen also from FIGS. 36 and 37. As best shown in FIG. 35, the fourth and the fifth levers 320 and 321 are in partly overlapping relationship at their respective edges 320a and 321b. A pin 331 is formed on the fifth lever 321 for engagement with a bend 320b of the fourth layer 320. The aforesaid bracket 3m includes a bend 3n adapted to prevent the clockwise turn, as seen in FIG. 35, of the fifth lever 321.

A locking lever 322 turnably pinned at 335 on the rear cover 3 is adapted to hold the latch apparatus in the locked or unlocked position as required with the aid of a spring 330 and stops 3p and 3q.

An opening lever 323 is turnably pinned at 336 on a downward extension 322a of the locking lever 322, and the left hand end, as seen in FIG. 35, of the opening lever is loosely received in a guide slot 3s of a bracket 3r formed on the rear cover 3 in order to limit the angle of swing of the opening lever, as will be seen also from FIG. 37. A helical extension spring 328 has its terminal hooks caught in a hole 323c of the opening lever 323 and a hole 321h of the fifth lever 321 thereby normally holding these levers in the positions illustrated in FIG. 35.

As seen in FIGS. 35, 36 and 37, a link 324 has its end 324a affixed at 325 to the fourth lever 320 and its other end 324b disposed in a position engageable with a recess 323d formed in the opening lever 323. The said other end of the link 324 is bent at right angle to loosely extend through a slot 3t formed in the rear cover 3 and, as best shown in FIGS. 36 and 37, slidably holds the rear cover between its terminal hook 324d and a ring 337 in order to maintain the major portion of the link at a required distance from the face of the rear cover.

A helical extension spring 326 extends between supports 219b and 322c formed on the third lever 219 and the locking lever 322 respectively, in such a manner that no substantial tension is normally exerted thereon. It is to be noted that this spring 326 is capable of resisting a greater tensile force than the spring 225 extending between the first lever 110 and the third lever 219. An inside opening lever 329 is turnably pinned at 338 on the bracket 3r formed on the rear cover 3, and its lower end 329a is disposed in a position engageable with the lateral extension 323b of the opening lever 323 as best shown in FIG. 37.

In the operation of this fifth embodiment of the invention constructed substantially as described above, the U-shaped arm 9a of the striker assembly 9 shown in FIGS. 7 and 8 enters the first guide groove 1f of the frame 1 and advances toward the edge 110a of the first lever 110 and the tip 105b of the detent 105 upon closure of the vehicle door. The advancing striker arm 9a

first causes the first lever 110 to turn clockwise, as seen in FIG. 35, on the pin 111 thereby exerting tension on the spring 116. The second lever 112 thus becomes loaded by the spring 116 in the counterclockwise direction to apply downward pressure on the bolt 104 with its free end 112c resting on the head 117a of the pin 117 as best illustrated in FIG. 38. However, since the bolt 104 is still held in its fully elevated position by the detent 105, the spring 116 is temporarily held extended to store the tension exerted thereon.

As the striker arm advances further along the first guide groove 1f, the detent 105 becomes disengaged from the bolt 104, with the result that the bolt is forced rapidly down to the secondary latched position by virtue of the tensile force that has been stored in the spring 116. As already mentioned in relation to the preceding examples, the abutments 104a and 104c of the bolt 104 are in contact with the striker arm in this secondary latched position.

The continued advancement of the striker arm causes the bolt 104 to be again forced down to the fully latched position by the energy still remaining in the spring 116. The bolt 104 is now partly received in the third guide groove 1b across the first guide groove 1f and is in contact with the striker arm at its abutment 104b. If now a locking knob, key or the like, not shown, is manipulated to lock the striker arm in this fully latched position, the locking lever 322 will assume the position shown in FIG. 39, whereby the vehicle door cannot be opened if its outside or inside handle, not shown, is manipulated to turn the opening lever 323.

In order to open the door, the opening lever 323 must be turned clockwise as seen in FIG. 35 by exerting pressure on its right hand end 323a by the manipulation of the outside handle, or by exerting pressure on its left hand end 323b via the inside opening lever 329 by the manipulation of the inside handle. This clockwise rotation of the opening lever 323 causes the clockwise rotation of the fourth lever 320 on the pin 333 via the link 324, and during this clockwise turning of the fourth lever 320, its edge 320a engages the rear end 119c, indicated by the intermittent lines in FIG. 35, of the release lever 119. Since the downward extension 119b of this release lever is received in the recess 117c of the pin 117 as best shown in FIG. 38, the upward turn of the release lever causes retraction of the head 117a of the pin into the hole 104e of the bolt 104, so that the free end 112c of the second lever 112 now becomes disengaged from the pin head 117a. As the bolt 104 is slightly raised by the continued clockwise turn of the fourth lever 320, the bend 320b of this fourth lever comes into contact with the pin 331 on the fifth lever 321. Therefore, as the fourth lever 320 is further turned clockwise by the link 324, the fifth lever 321 becomes effective to raise the release lever 119, with the edge 321b of the former in contact with the rear end 119c of the latter. It will accordingly be apparent that a relatively slight angular displacement of the opening lever 323 results in a greater angle of swing of the fifth lever 321, which thus operates to move the bolt 104 to its fully elevated position and hence to permit disengagement of the striker arm from the latch apparatus.

The self-cancelling operation according to this fifth embodiment can be accomplished as follows. It is assumed that while the door is open, the locking knob or the like is manipulated to turn the locking lever 322 to the locking position as shown in FIG. 40, and that the

door is then closed without manipulating the outside handle, that is, with the opening lever 323 held in the position indicated by the dot-and-dash lines in FIG. 40. Then the striker arm advancing along the first guide groove 1f causes a clockwise rotation of the first lever 110 in the normal manner, with the result that the third lever 219 is displaced downward until it abuts against the stop 3f formed on the rear cover 3. This downward displacement of the third lever 219 exerts tension on the spring 326 and hence returns the locking lever 221 to the unlatching position. The continued advancement of the striker arm along the first guide groove causes further clockwise turning of the first lever 110. However, since now the third lever 219 is already in contact with the stop 3f substantially at its midpoint, the right hand end 219b of this third lever is caused to turn counter-clockwise on the pin 229 against the force of the spring 225. When the striker arm has reached the fully latched position, the right hand end of the third lever 219 is returned to a position substantially the same as that it assumed before the door was closed. It is accordingly possible to turn the locking lever 221 to the locking position by the locking knob or the like in the ordinary manner after the door is fully closed.

This fifth embodiment of the invention also permits the keyless locking of the striker arm to the patch apparatus. To this end it is necessary that while the door is open, the locking knob be manipulated to turn the locking lever 322 to the locking position as shown in FIG. 40, and that the outside handle be further manipulated to maintain the opening lever 323 in the position indicated by the solid lines in the same drawing when the door is closed. The first lever 110 is turned clockwise as aforesaid by the striker arm advancing along the first guide groove 1f, with the result that the third lever 219 is displaced downward until it comes into contact with the stop 3f on the rear cover 3. The third lever 219 thus exerts tension on the spring 326 thereby causing the locking lever 322 to tend to return to the unlocking position. However, since the arcuate edge 323e of the opening lever 323 now abuts on the bent end 324b of the link 324, the locking lever 322 is unable to return to the unlocking position, and the spring 326 remains only extended.

The continued advancement of the striker arm along the first guide groove 1f causes further clockwise turning of the first lever 110, with the result that the third lever 219, now in contact with the stop 3f, is caused to turn counter-clockwise on the pin 229 against the force of the spring 225. Hence, when the striker arm has reached the fully latched position, the right hand end 219 of the third lever is returned to the position substantially the same as that it assumed before the door was closed. No substantial tension is now exerted on the spring 326, so that the locking lever 322 will not return to the unlocking position if the outside handle is released to permit the opening lever 323 to return to the position indicated by the dot-and-dash lines in FIG. 40. The keyless locking of the vehicle door is thus accomplished.

It is to be noted that in this final embodiment of the invention, the edge 323e of the opening lever 323 is arched in shape about the axis of rotation of the opening lever, so that once the locking lever is turned to the locking position as shown in FIG. 40, this arcuate edge 323e of the opening lever is capable of positively abutting on the bent end 324b of the link 324 to retain the

locking lever in the locking position in spite of the force exerted through the spring 326. The shape of the recess 323d in the opening lever is also well calculated to positively engage the bent end of the link as required.

What we claim is:

1. A door latch device for cooperative use with a striker, comprising:

A frame having a first guide groove adapted to receive said striker, a second guide groove extending normally to and communicating with said first guide groove, and a third guide groove aligned with said second guide groove across said first guide groove;

a bolt slidable along and through said second and third guide grooves;

detent means normally engaging said bolt to hold the same in said second guide groove, said detent means being disengaged from said bolt upon entrance of said striker into said first guide groove; a first lever turnably supported on one side of said frame and being turned in a predetermined direction upon entrance of said striker into said first guide groove before said detent means is disengaged from said bolt;

an extension spring having one end thereof coupled to the free end of said first lever; and

a second lever turnably supported on said one side of said frame and having a free end coupled to the other end of said extension spring and held against said bolt in such a manner that no substantial tension is normally exerted on said extension spring, whereby said extension spring is stretched when said first lever is turned in said predetermined direction upon entrance of said striker into said first guide groove, the energy thus stored in said extension spring being utilized to cause said second lever to force said bolt to slide in said second groove toward said third guide groove when said detent means is thereafter disengaged from said bolt.

2. A door latch device as defined in claim 1 wherein said striker is of the type having a substantially U-shaped striker arm.

3. A door latch device as defined in claim 1 wherein that end of said bolt directed toward said third guide groove is recessed to define abutments adapted to engage said striker in a secondary latched position.

4. A door latch device as defined in claim 1 including means for facilitating the release of said striker from said first guide groove, said means comprising:

A pin slidably extending through a bore formed transversely through said bolt, said pin being urged in one direction by spring means whereby one end of said pin normally projects out of said bore to engage said second lever; and

a release lever turnably coupled to said bolt to move the same out of engagement with said striker, said release lever including a portion engaging the other end of said pin, which also projects out of said bore, in such a manner that when said release lever is operated to move said bolt out of engagement with said striker, said pin is caused to move in the other direction against the force of said spring means until said one end of said pin is withdrawn into said bore out of engagement with said second lever.

5. A door latch device for cooperative use with a striker, comprising:

A frame having a first guide groove adapted to receive said striker, a second guide groove extending normally to and communicating with said first guide groove, and a third guide groove aligned with said second guide groove across said first guide groove;

a main bolt slidably received in said second guide groove so as to be slidable into and away from said first guide groove;

first spring means urging said main bolt toward said third guide groove;

detent means normally engaging said main bolt to hold the same in said second guide groove against the force of said first spring means, said detent means being disengaged from said main bolt upon entrance of said striker arm into said first guide groove;

an auxiliary bolt coupled to said main bolt so as to be turnable in one direction only relative to said main bolt against the force of second spring means, said auxiliary bolt including a portion normally projecting into said first guide groove in a manner such that upon entrance of said striker into said first guide groove, said auxiliary bolt is caused to temporarily retract into said second guide groove together with said main bolt against the force of said first spring means before said detent means is disengaged from said main bolt, thereby permitting said striker to advance therewith, whereby when said detent means is successively disengaged from said main bolt, said main bolt is caused by said first spring means to project into said first guide groove while said auxiliary bolt is received in said third guide groove; and

release means normally preventing the rotation of said auxiliary bolt in said one direction relative to said main bolt, said release means being operable to permit said auxiliary bolt to be turned in said one direction by said striker to permit the latter to escape from said first guide groove.

6. A door latch device as defined in claim 5 wherein said striker is of the type having substantially U-shaped striker arm.

7. A door latch device as defined in claim 5 wherein said auxiliary bolt is recessed to define an abutment adapted to engage said striker in a secondary latched position in cooperation with an adjacent edge of said main bolt.

8. A door latch device as defined in claim 5 wherein said release means comprises:

A pin slidably extending through a bore formed transversely through said main bolt, said pin being urged in one direction by third spring means whereby one end of said pin normally projects out of said bore to engage said auxiliary bolt, thereby preventing the same from turning in said one direction relative to said main bolt; and

a release lever turnably coupled to said main bolt to move both of said main and auxiliary bolts out of engagement with said striker, said release lever including a portion engaging the other end of said pin which also projects out of said bore, in a manner such that when said release lever is operated to move said main and auxiliary bolts out of engagement with said striker, said pin is caused to move in the other direction against the force of said third spring means until said one end of said pin is with-

drawn into said bore out of engagement with said auxiliary bolt.

9. A door latch device as defined in claim 4 further comprising:

A third lever pivotally supported on said first lever; means for regulating the motion of said third lever in

a manner such that upon rotation of said first lever in said predetermined direction, said third lever is first caused to revolve around the axis of rotation of said first lever in the same direction therewith through a predetermined angle and then to turn on its own pivot point in the opposite direction until at least one free end of said third lever returns to substantially the same position as that it assumed before said first lever was turned in said predetermined direction thereof;

a locking lever turnably supported on said one side of said frame so as to be turnably between a door locking position and a door unlocking position; an opening lever pivotally supported on said locking lever at a position offset from the axis of rotation of the latter whereby said opening lever is pivotable on its own pivot between a normal position and a door opening position independently of said locking lever while also being revolved around the rotational axis of said locking lever as the latter is turned between said door locking and unlocking positions thereof;

a fourth lever turnably supported at a point intermediate between the two ends thereof on said one side of said frame, said fourth lever having one end thereof disposed in a position engageable with said opening lever when said locking lever is in said door unlocking position and unengageable with said opening lever when said locking lever is in said door locking position, the other end of said fourth lever being disposed in a position engageable with said release lever, whereby when said opening lever is turned from said normal position to said door opening position while said locking lever is in said door unlocking position, said fourth lever is turned to operate said release lever in a manner such that said bolt is moved out of engagement with said striker received in said first guide groove; and

a second extension spring extending between said one free end of said third lever and said locking lever in a manner such that no substantial tension is normally exerted on said second extension spring, whereby upon closure of the door while said locking lever is in said door locking position and said opening lever in said normal position, said locking lever is automatically returned to said door unlocking position to permit the device to perform a self-cancelling operation, and whereby upon closure of the door while said locking lever is in said door locking position and said opening lever in said door opening position, said locking lever is prevented from returning to said door unlocking position to permit the device to perform a keyless locking operation since then said opening lever abuts against said one end of said fourth lever.

10. A door latch device as defined in claim 1 comprising:

a release lever turnably coupled to said bolt to move the same out of engagement with said striker;

a striker responsive lever turnably supported on one side of said frame, provided with a spring disposed between said lever and said frame and being turned in a predetermined direction against biasing force of said spring upon entrance of said striker into said first guide groove before said detent means is disengaged from said bolt;

a third lever pivotally supported on said first lever; means for regulating the motion of said third lever in a manner such that upon rotation of said first lever in said predetermined direction, said third lever is first caused to revolve around the axis of rotation of said first lever in the same direction therewith through a predetermined angle and then to turn on its own pivot point in the opposite direction until at least one free end of said third lever returns to substantially the same position as that it assumed before said first lever was turned in said predetermined direction thereof;

a locking lever turnably supported on said one side of said frame so as to be turnably between a door locking position and a door unlocking position;

an opening lever pivotally supported on said locking lever at a position offset from the axis of rotation of the latter whereby said opening lever is pivotable on its own pivot between a normal position and a door opening position independently of said locking lever while also being revolved around the rotational axis of said locking lever as the latter is turned between said door locking and unlocking positions thereof;

a fourth lever turnably supported at a point intermediate between the two ends thereof on said one side of said frame, said fourth lever having one end thereof disposed in a position engageable with said opening lever when said locking lever is in said door unlocking position and unengageable with said opening lever when said locking lever is in said door locking position, the other end of said fourth lever being disposed in a position engageable with said release lever, whereby when said opening lever is turned from said normal position to said door opening position while said locking lever is in said door unlocking position, said fourth lever is turned to operate said release lever in a manner such that said bolt is moved out of engagement with said striker received in said first guide groove; and

a second extension spring extending between said one free end of said third lever and said locking lever in a manner such that no substantially tension is normally exerted on said second extension spring, whereby upon closure of the door while said locking lever is in said door locking position and said opening lever in said normal position, said locking lever is automatically returned to said door unlocking position to permit the device to perform a self-cancelling operation, and whereby upon closure of the door while said locking lever is in said door locking position and said opening lever in said door opening position, said locking lever is prevented from returning to said door unlocking position to permit the device to perform a keyless locking operation since then said opening lever abuts against said one end of said fourth lever.

11. A door latch device as defined in claim 9 wherein that end of said bolt directed toward said third guide

groove is recessed to define abutments adapted to engage said striker in a secondary latched position.

12. A door latch device as defined in claim 9 wherein said means for regulating the motion of said third lever comprises:

A third extension spring extending between said first and third levers to urge the latter in said predetermined direction of rotation of said first lever; and a stop adapted to make contact with said third lever at a point intermediate between the two ends thereof when the same has been revolved around the axis of rotation of said first lever through said predetermined angle.

13. A door latch device as defined in claim 4 further comprising:

a locking lever supported on said one side of said frame so as to be turnable between a door locking position and a door unlocking position;

an opening lever turnably supported on said locking lever at a position offset from the axis of rotation of the latter whereby said opening lever is turnable on its own rotational axis between a normal position and a door opening position independently of said locking lever while also being revolved around the rotational axis of said locking lever as the latter is turned between said door locking and unlocking positions thereof;

a fourth lever turnably supported on said one side of said frame, said fourth lever having one edge engageable with said release lever and being turnable in a predetermined direction to operate said release lever;

a fifth lever turnably supported on said one side of said frame in partly overlapping relationship to said fourth lever, said fifth lever also having one edge engageable with said release lever and having means to be turned in a predetermined direction to operate said release lever upon turning of said fourth lever in said predetermined direction thereof; and

linkage means capable of operatively interconnecting said opening lever and said fourth lever when said locking lever is in said door unlocking position and of disconnecting said opening lever from said fourth lever when said locking lever is in said door locking position, whereby when said opening lever is turned from said normal position to said door opening position while said locking lever is in said door unlocking position, said fourth and fifth levers are successively turned to operate said release lever in a manner such that said bolt is moved out of engagement with said striker received in said first guide groove.

14. A door latch device as defined in claim 13 further comprising:

A third lever turnably supported on said first lever; means for regulating the motion of said third lever in a manner such that upon rotation of said first lever in said predetermined direction, said third lever is first caused to revolve around the axis of rotation of said first lever in the same direction therewith through a predetermined angle and then to turn on its own turning axis in the opposite direction until at least one free end of said third lever returns to substantially the same position as that it assumed before said first lever was turned in said predetermined direction thereof;

a second extension spring extending between said one free end of said third lever and said locking lever in a manner such that no substantial tension is normally exerted on said second extension spring, whereby upon closure of the door while said locking lever is in said door locking position and said opening lever in said normal position, said locking lever is automatically returned to said door unlocking position to permit the device to perform a self-cancelling operation, and whereby upon closure of the door while said locking lever is in said door locking position and said opening lever is in said door opening position, said locking lever is prevented from returning to said door unlocking position to permit the device to perform a keyless locking operation since then said opening lever is held immovable by said linkage means.

5

10

15

15. A door latch device as defined in claim 13 wherein that end of said bolt directed toward said third guide groove is recessed to define abutments adapted to engage said striker in a secondary latched position.

16. A door latch device as defined in claim 13 wherein said means for regulating the motion of said third lever comprises:

A third extension spring extending between said first and third levers to urge the latter in said predetermined direction of rotation of said first lever; and a stop adapted to make contact with said third lever at a point intermediate between the two ends thereof when the same has been revolved around the axis of rotation of said first lever through said predetermined angle.
